DOOR HANDLE AND LIKE FASTENING

Robert Grimmond, Voorburg, The Hague, Netherlands

Application April 19, 1937, Serial No. 137,874
In Great Britain April 22, 1936

18 Claims. (Cl. 292—353)

This invention relates to door handle and like assemblies of the kind wherein a handle or equivalent is securable to a spindle by means engageable with or disengageable from a recess in the spindle by rotation of an actuating member relative to the handle or equivalent. For convenience of description, reference is hereinafter and in the appended claims made to door handle assemblies, but it will become apparent that the invention is not limited in its application to door handles and may be used for many other purposes where it is required to retain a spindle in a socket.

An object of the present invention is to provide an improved door handle assembly of the kind referred to, in which the or each handle can be secured firmly to the spindle (quite independently of the woodwork and without the use of tapered pins or grub screws and similar objectionable fastening means as commonly employed) in substantially any desired position along the spindle.

Another object is to enable the or each handle together with a cover plate (which may be a rose or a finger plate) to be rapidly and easily attached and detached without first having to insert or remove troublesome short screws such as are commonly employed for securing the cover plate to the door.

Still another object is to provide a door handle assembly having standardized parts, but, nevertheless, attachable to doors of various thicknesses, with provision for adjustment within limits of a fineness not hitherto attained except with screwed spindles.

With these and other objects in view, the invention provides a door handle or like assembly of the kind referred to, characterized in that the spindle is retained in the socket by spring retaining means anchored to a carrier member rotatable relative to the socket, so that partial relative turning movement of the carrier member and socket enables the spring retaining means to pass through apertures in the socket into engagement with grooves formed in the spindle, or forces the spring means out of engagement, as desired.

The socket preferably comprises or supports a radial flange which serves to hold the carrier member rotatably, but not displaceable axially, in assembly therewith. The same flange may also serve to hold a spindle cover plate rotatably in assembly with the carrier member and the socket, thereby enabling the handle to be removed from the door with the cover plate as a unit.

In the assembly according to the invention, the retaining means is preferably constituted by at least one U-shaped spring adapted to pass through an opposed pair of apertures in the socket into engagement with grooves in opposite surfaces of the spindle. The base of the or each U-shaped spring is anchored to the carrier member

by projections serving for the mounting of the spring with its limbs resiliently free.

The aforesaid grooves may at one end of the spindle be spaced differently from grooves at the other end of the spindle, to enable fine adjustment of a pair of sockets or handles to say any thickness of door in a manner which will herein-after be described. Alternatively, the assembly may include a tandem plurality of retaining means, such as the U-shaped springs above mentioned, the spacing of which is different from the spacing of the grooves in the spindle, so that the engagement of one or another of the retaining means with a groove or pair of grooves enables fine adjustment of a socket or handle on the spindle.

Two embodiments of the invention will be described, by way of example, with reference to the accompanying drawings, wherein:

Fig. 1 is a side view, partly in section, of a pair of door handles mounted on a common spindle;

Fig. 2 is a transverse view on the line II—II of Fig. 1;

Fig. 3 represents a section on the line III—III of Fig. 1 with the handle removed and the cover plate not shown;

Fig. 4 is an axial section, on an enlarged scale, of a handle socket member;

Fig. 5 is an end view of the same;

Figs. 6 and 7 are respectively front and end views, also on an enlarged scale, of a U-shaped spring retaining means;

Fig. 8 is a side view of the spindle;

Fig. 9 is a transverse section of the same;

Fig. 10 is an axial section of a modified handle assembly; and

Fig. 11 is a section on the line XI—XI of Fig. 10, with the handle and cover plate not shown.

In the embodiment shown in Figs. 1 to 9, the handle socket 1 is of square section and is secured in a nut 2 embedded in the handle 3 by means of a screw 4 inserted into the nut through a hole 5 in the blind end 6 of the socket. The other end of the socket, which is open to receive the spindle 7, (also of square section) has an external shoulder 8 which serves as a bearing for a carrier ring 9 disposed between a cover plate 12 and the handle 3, and a radial flange 10 with a rim 11 which centralizes the carrier ring and the spindle cover plate and holds the ring in place in assembly with the handle.

Extending through two opposite sides of the square sectioned socket 1 are slots 13 (Fig. 4). A U-shaped spring 14 (see Figs. 6 and 7) is anchored to the carrier ring 9 by two integral projections 15 at its base, pressed into one pair of holes 16 in the ring 9, and the limbs 17 of the spring, which are curved inwardly towards one another, are thereby adapted to project through the aforesaid slots 13 into engagement with any

selected pair of a number of grooves 18 or 18a formed in the spindle 7 (see Figs. 8 and 9). Terraces 19, formed within the ring 9, afford bearings for the shank of the handle 3 and thereby maintain a space within which the spring 14 is free to move. The ends of the limbs are turned as shown in Fig. 6 to facilitate mounting and removal of the spring on and from the socket.

In the assembly of the various parts of a handle, the cover plate 12 is first mounted on the rim 11 of the socket member 1. The carrier ring 9 with a retaining spring in position is then passed over the socket member 1 with the limbs 17 of the spring spread apart so that they slide down those sides of the portion thereof which are not slotted until the carrier ring is located about the shoulder 8 and loosely within the inner periphery of the cover plate 12. The handle 3 is then passed over the socket member 1 until its shank enters the carrier ring 9 whereafter the assembly is completed by threading the screw 4 through the hole 5 in the blind end 6 of the socket member into the nut 2, which is embedded in the handle. The carrier ring 9 and the cover plate 12 are rotatable relative to one another and to the socket member 1, the latter, of course, being non-rotatable with respect to the handle 3.

So that the relative angular positions of the various parts may be known after assembly, the cover plate 12 has on its inner surface an opposed pair of grooves 20, which may be aligned with a diametrical groove 21 across the flange 10 of the socket member 1. The rim 22 of the carrier ring 9 also has a diametrically opposed pair of notches 23 (Fig. 3). These grooves and notches are so disposed that when the notches 23 in the ring 9 are at right angles to the groove 21, the limbs 17 of the spring 14 are resting on the unslotted sides of the socket member. The slotted sides of said member are indicated by the groove 21.

When it is desired to secure a pair of handles to a door, one of the handles, assembled as above described, is slid on to the spindle as far as is considered necessary, with the groove 21 directed towards the grooved sides of the spindle. The ring 9 is then turned through 90°, whereby the limbs 17 of the spring 14 pass through the slots 13 in the socket member 1 into engagement with a pair of grooves 18 in the spindle 7.

The free end of the spindle 7, with one handle attached thereto, is passed through the usual square hole in the lock or latch until the end of the spindle with the grooves 18a projects from the other side of the door. The second handle, whose parts have previously been assembled and set in the relative positions above described, as indicated by notches 23 and the groove 21, is then slid on to the spindle, and the two cover plates are pressed towards one another until their flat faces engage the surface of the door. The carrier ring 9 of the second handle is then turned through 90°, whereby the limbs 17 of its retaining spring 14, penetrating the slots 13 in the socket member 1, engage a pair of the grooves 18a in the spindle.

For firmly securing the pair of handles to the door and eliminating rattle, the inner surfaces 24 of the spindle cover plates 12 are each provided with a set of pins 25 arranged to penetrate the surface of the door and prevent the plate 12 from rotating. Preferably, these pins are disposed asymmetrically, as shown in Fig. 2, to ensure that the plates 12 are returned to their original positions in the event of their having

been removed, as for the painting of the door. This is particularly desirable in the case of non-circular cover plates.

The difference in the spacings of the grooves 18 and the grooves 18a enables very fine adjustment of the handle without the necessity for extremely close spacing of the grooves. For example, if the grooves 18 are disposed $\frac{1}{16}$ " apart, and the grooves 18a are disposed $\frac{3}{32}$ " apart (pitch spacing), the pair of handles are finely adjustable to doors of thicknesses varying by as little as $\frac{1}{32}$ ". Evidently, by advancing one handle from one of the pairs of grooves 18a to the next pair inwards, and by retracting the other handle from one of the pairs of grooves 18 to the next pair outwards, the net result is a reduction of the distance between the surfaces 24 of the cover plates 12 by $\frac{1}{32}$ ", and vice versa.

In an alternative arrangement, the grooves may all be equally spaced apart, and the handles 20 may be provided with pluralities of retaining means, such as the U-shaped springs 14 illustrated.

It will be appreciated that when a pair of handles have been secured to a door as described, they may be freely used without possibility of the locking means being accidentally released. The carrier ring 9 rotates with the handle by virtue of the engagement of the limbs 17 of the retaining spring 14 with the ends of the slots 13 in the socket member 1. A deliberate grip at two opposed points on the rim 22 of the ring 9 is necessary before the ring and the handle can be relatively rotated. However, by such deliberate action the locking of the handle to the spindle 7 is very conveniently and quickly released to enable the handle assembly, namely, the handle 3, the ring 9 and the cover plate 12, to be withdrawn as a unit.

Obviously, fastening means according to the invention may be applied to a single door handle, or to one of a pair of door handles wherein the other handle is permanently attached to the spindle.

The fastening means is entirely concealed and is such that it cannot readily be tampered with. The external periphery or rim 22 of the carrier ring 9 is, as shown, flush with the external surfaces of the cover plate 12 and the shank of the handle 3 so that said rim can be turned, relatively to the handle, deliberately by the fingers, but is not liable to be turned accidentally.

However, in an alternative construction as shown in Figs. 10 and 11, the periphery of a modified carrier ring 26 is sunk within the confines of the shank of the handle 3 and a modified cover plate 27, so that it is inaccessible except with the aid of a special tool. In this construction, the socket member 28 is also modified, having at its inner end a boss 29 in place of the flange 10 shown in Fig. 1. The boss 29 supports a bearing ring 30, about the outer, tapered periphery 31 of which the annular cover plate 27 is freely rotatable. The carrier ring has a peripheral flange 32 which surrounds a shoulder 33 on the bearing ring 30, and the outer part of the carrier ring is lodged within a peripheral flange 34 on the handle shank. In the recess 35 of the carrier ring 26 there are, as shown in Fig. 11, a number of projections, namely, a triangular projection 36 extending inwards from the peripheral flange 32, two trapezoidal projections 37 symmetrically spaced relative to the projection 36, and three other projections 38 spaced about the periphery. 75

The inner, transverse surfaces of all the projections engage the outer surface of the bearing ring 30 so as to create an annular space 39 (Fig. 10) for the accommodation of a modified, flat retaining spring 40. The upper part 41 of this spring is of M-shape, and adapted to be engaged between the projections 36 and 37 as shown in Fig. 11, whereby the elimination of the projections 15 on the spring as shown in Figs. 6 and 7 is enabled. The limbs of the spring 40 are of curved shape like the limbs 17 as shown in Fig. 6, and adapted to pass through slots 13 in the socket member 28 into an opposed pair of recesses 18 in the spindle 7 as hereinbefore described.

The operations of assembling and dismantling a handle assembly according to Figs. 10 and 11 are similar to those above described. However, as the cover plate 27 shrouds the carrier ring 26, the latter is not actuatable by the fingers for rotation relative to the handle in order to engage or disengage the retaining spring 40 with or from the grooves 18. It is therefore provided with recesses 42 (Fig. 11) in the periphery of its outer part, adapted to be engaged by a tool, such as a C-spanner, inserted in the small gap 43 between the cover plate 27 and the peripheral flange 34 of the handle.

Evidently, in this construction, the carrier ring 26 and the bearing ring 30 turn with the handle and the socket 28. There is ample clearance between the outer periphery of the carrier ring 26 and the inner periphery of the cover plate 27, so that when the latter is non-rotatably secured to the surface of a door by the pins 25 it does not tend to bind upon the carrier ring and enable the handle in use to be turned relative to said ring. Thus, the handle may be freely used and is not able to be removed except by the deliberate use of the tool to cause relative turning of the carrier ring and the handle.

Many modifications may be made without departing from the invention. For instance, the flange 10 of the socket member 1 may be substituted by a separate disc held on said member by a relatively small integral collar or head, the various parts being so constructed that said collar or head is sunk within the face 24 of the cover plate 12 (Fig. 1). The cover plate itself may be polygonal or of ornamental shape instead of circular as illustrated, and it may in fact form an integral part of a lock guard or finger plate. Moreover, if desired, the cover plate may be entirely omitted.

Evidently, the spindle and the handle socket may have polygonal sections other than square or rectangular (or as in the case of twin spindles, even a round section) and the handles may be made in various shapes for convenience or artistic appearance, including lever types.

I claim:—

1. A door handle assembly comprising, in combination, a spindle, a recess in the spindle, a socket turnable with the spindle and having at least one apertured side, a handle turnable with the socket, a carrier member turnable on the socket relative to the handle, and spring retaining means anchored to the carrier member and disposed to pass through said apertured side into engagement with said recess under a partial relative turning of the handle and the carrier member and to move out of engagement with said recess and ride on said socket under another partial relative turning of the handle and the carrier member.

2. A door handle assembly comprising, in combination, a spindle, a recess in the spindle, a socket turnable with the spindle and having at least one apertured side, a handle turnable with the socket, a carrier member, a radial flange supported by the socket, said flange serving to hold the carrier member rotatably in assembly with the socket and the handle, and spring retaining means anchored to the carrier member and disposed to pass through said apertured side into engagement with said recess under a partial relative turning of the handle and the carrier member and to move out of engagement with said recess and ride on said socket under another partial relative turning of the handle and the carrier member.

3. A door handle assembly comprising, in combination, a spindle, a recess in the spindle, a socket turnable with the spindle and having at least one apertured side, a handle turnable with the socket, a spindle cover plate, a carrier member, a radial flange on the socket, said flange serving to hold the carrier member rotatably in assembly with the socket and the handle and also to hold the cover plate rotatably in assembly with the socket, and spring retaining means anchored to the carrier member and disposed to pass through said apertured side into engagement with said recess under a partial relative turning of the handle and the carrier member and to move out of engagement with said recess and ride on said socket under another partial relative turning of the handle and the carrier member.

4. A door handle assembly comprising, in combination, a spindle, at least one pair of recesses in opposite sides of the spindle, a socket turnable with the spindle and having an opposed pair of apertured sides, a handle turnable with the socket, a carrier member turnable on the socket relative to the handle, and retaining means constituted by a U-shaped spring anchored to the carrier member with its limbs disposed to pass one through each of said apertured sides into engagement with each of said recesses under a partial relative turning of the handle and the carrier member and to move out of engagement with said recesses and ride on said socket under another partial relative turning of the handle and the carrier member.

5. A door handle assembly comprising, in combination, a spindle, at least one pair of recesses in opposite sides of the spindle, a socket turnable with the spindle and having an opposed pair of apertured sides, a handle turnable with the socket, a carrier ring, a radial flange supported by the socket, said flange serving to hold the carrier ring rotatably in assembly with the socket and the handle, at least one pair of axial holes in said ring, retaining means constituted by a U-shaped spring, and a pair of perpendicular projections from the base of said spring spaced to enter said pair of holes and thereby to anchor said spring to the carrier ring with its limbs disposed to pass one through each of said apertured sides into engagement with each of said recesses under a partial relative turning of the handle and the carrier member and to move out of engagement with said recesses and ride on said socket under another partial relative turning of the handle and the carrier member.

6. A door handle assembly comprising, in combination, a spindle, a plurality of pairs of recesses in opposite sides of one end of the spindle spaced apart with equal pitch, a plurality of pairs of recesses in opposite sides of the other end of the

spindle spaced apart with equal pitch different from said first-mentioned pitch, a pair of sockets mountable on the ends of the spindle for turning therewith and each having an opposed pair of apertured sides, a handle turnable with each socket, a carrier ring mounted on each socket, a radial flange on each socket serving to hold the carrier ring rotatably in assembly with the socket and the handle, at least one pair of axial holes in said ring, retaining means constituted by a U-shaped spring, and a pair of perpendicular projections from the base of said spring spaced to enter said pair of holes and thereby to anchor said spring to the carrier member with its limbs disposed to pass each through one of said apertured sides into engagement with one of said recesses under a partial relative turning of the handle and the carrier member and to move out of engagement with said recesses and ride on said socket under another partial relative turning of the handle and the carrier member.

7. A door handle assembly comprising, in combination, a spindle, at least one pair of grooves in opposite sides of the spindle, a socket turnable with the spindle and having an opposed pair of apertured sides, a handle turnable with the socket, a carrier member turnable on the socket relative to the handle, retaining means constituted by a U-shaped spring, and mutually co-operating recesses and projections on said carrier member and said spring serving to anchor said spring by its base to the carrier member with its limbs disposed to pass one through each of said apertured sides into engagement with each of said grooves under a partial relative turning of the handle and the carrier member and to move out of engagement with said grooves and ride on said socket under another partial relative turning of the handle and the carrier member.

8. A door handle assembly comprising, in combination, a spindle, at least one pair of recesses in opposite sides of the spindle, a socket turnable with the spindle and having an opposed pair of apertured sides, a handle turnable with the socket, a carrier ring, a radial flange supported by the socket, said flange serving to hold the carrier ring rotatably in assembly with the socket and the handle, retaining means constituted by a U-shaped spring, the base of said spring being M-shaped, a plurality of projections on said ring adapted to engage in the angles of said base and thereby to anchor said spring to the carrier ring with its limbs disposed to pass each through one of said apertured sides into engagement with one of said recesses under a partial relative turning of the handle and the carrier member and to move out of engagement with said recesses and ride on said socket under another partial relative turning of the handle and the carrier member.

9. A door handle assembly comprising, in combination, a spindle, a plurality of pairs of recesses in opposite sides of one end of the spindle spaced apart with equal pitch, a plurality of pairs of recesses in opposite sides of the other end of the spindle spaced apart with equal pitch different from said first mentioned pitch, a pair of sockets mountable on the ends of the spindle for turning therewith and each having an opposed pair of apertured sides, a handle turnable with each socket, a carrier ring mounted on each socket, a radial flange on each socket serving to hold the carrier ring rotatably in assembly with the socket and the handle, retaining means constituted by a U-shaped spring, the base of said spring being M-shaped, a plurality of projections

on said ring adapted to engage in the angles of said base and thereby to anchor said spring to the carrier ring with its limbs disposed to pass one through each of said apertures into engagement with each of said recesses under a partial relative turning of the handle and the carrier member and to move out of engagement with said recesses and ride on said socket under another partial relative turning of the handle and the carrier member.

10. A door handle assembly comprising, in combination, a spindle, a plurality of recesses spaced apart with equal pitch in one end of the spindle, a plurality of recesses spaced apart with equal pitch different from said first-mentioned pitch in the other end of the spindle, a pair of sockets mountable on the ends of the spindle for turning therewith and each having at least one apertured side, a handle turnable with each socket, a carrier member turnable on each socket relative to said handle, and spring retaining means anchored to the carrier member and disposed to pass each through one of said apertured sides into engagement with one of said recesses under a partial relative turning of the handle and the carrier member and to move out of engagement with said recesses and ride on said socket under another partial relative turning of the handle and the carrier member.

11. A door handle assembly comprising, in combination, a rectangular spindle, a plurality of pairs of recesses spaced apart with equal pitch in opposite sides of one end of the spindle, a plurality of pairs of recesses spaced apart with equal pitch different from said first-mentioned pitch in opposite sides of the other end of the spindle, a pair of sockets of hollow rectangular cross-section mountable on the ends of the spindle for turning therewith and each having an opposed pair of apertured sides, a handle turnable with each socket, a spindle cover plate associated with each socket, a carrier member associated with each socket, a radial flange on each socket, said flange serving to hold the associated carrier member rotatably in assembly with the socket and the associated handle and also to hold the associated cover plate rotatably in assembly with the socket, and retaining means constituted by a U-shaped spring anchored to each carrier member with its limbs disposed to pass one through each of the apertured sides of the associated socket into engagement with one of said recesses under a partial relative turning of the handle and the carrier member and to move out of engagement with said recesses and ride on said socket under another partial relative turning of the handle and the carrier member.

12. A door handle assembly comprising, in combination, a spindle, a recess in the spindle, a socket turnable with the spindle and having at least one apertured side, a handle turnable with the socket, a carrier ring turnable on the socket relative to the handle, the periphery of said ring being exposed to enable turning thereof relative to the handle by the fingers, and spring retaining means anchored to the carrier ring and disposed to pass through said apertured side into engagement with said recess under a partial relative turning of the handle and the carrier ring and to move out of engagement with said recess and ride on said socket under another partial relative turning of the handle and the carrier ring.

13. A door handle assembly comprising, in combination, a spindle, at least one recess in the

- spindle, a socket turnable with the spindle and having at least one apertured side, a handle turnable with the socket, a carrier member, a spindle cover plate, a radial flange supported by the socket, said flange serving to hold the carrier member rotatably in assembly with the socket and the handle and also to hold the cover plate rotatably in assembly with the socket, said carrier member being sunk between the handle and the cover plate to prevent access thereto except by a tool insertable between said handle and cover plate, and spring retaining means anchored to the carrier member and disposed to pass through said apertured side into engagement with said recess under a partial relative turning of the handle and the carrier member and to move out of engagement with said recess and ride on said socket under another partial relative turning of the handle and the carrier member.

14. A door handle assembly comprising, in combination, a rectangular spindle, a plurality of pairs of recesses spaced apart with equal pitch in opposite sides of one end of the spindle, a plurality of pairs of recesses spaced apart with equal pitch different from said first-mentioned pitch in opposite sides of the other end of the spindle, a pair of sockets of hollow rectangular cross-section mountable on the ends of the spindle for turning therewith and each having an opposed pair of apertured sides, a handle turnable with each socket, a spindle cover plate associated with each socket, a carrier ring associated with each socket, a radial flange on each socket, said flange serving to hold the associated carrier ring rotatably in assembly with the socket and the associated handle and also to hold the associated cover plate rotatably in assembly with the socket, the periphery of each of said rings being sunk between the associated cover plate and handle for preventing access thereto except by a tool insertable between said cover plate and handle and retaining means constituted by a U-shaped spring anchored to each carrier member with its limbs disposed to pass one through each of the apertured sides of the associated socket into engagement with one of said recesses under a partial relative turning of the handle and the carrier ring and to move out of engagement with said recesses and ride on said socket under another partial relative turning of the handle and the carrier ring.

15. A door handle assembly comprising, in combination, a spindle, at least one pair of recesses in opposite sides of the spindle, a socket turnable with the spindle and having an opposed pair of apertured sides, a handle turnable with the socket, a carrier member turnable on the socket relative to the handle, and retaining means constituted by a U-shaped spring anchored to the carrier member with its limbs disposed to pass one through each of said apertured sides into engagement with each of said recesses under a partial relative turning of the handle and the carrier member and to move out of engagement with said recesses and ride on said socket under another partial relative turning of the handle and the carrier member.

16. A door handle assembly comprising, in combination, a spindle, at least one pair of recesses in opposite sides of the spindle, a socket turnable with the spindle and having an opposed pair of apertured sides, a handle turnable with the socket, a carrier ring, a radial flange supported by the socket, said flange serving to hold the carrier ring rotatably in assembly with the socket and the handle, the periphery of said ring being exposed to enable turning thereof relative to the handle by the fingers, retaining means constituted by a U-shaped spring, the base of said spring being M-shaped, and a plurality of projections on said ring adapted to engage in the angles of said base and thereby to anchor said spring to the carrier ring with its limbs disposed to pass each through one of said apertured sides into engagement with one of said recesses under a partial relative turning of the handle and the carrier member and to move out of engagement with said recesses and ride on said socket under another partial relative turning of the handle and the carrier member.

17. A door handle assembly comprising, in combination, a spindle, at least one pair of recesses in opposite sides of the spindle, a socket turnable with the spindle and having an opposed pair of apertured sides, a handle turnable with the socket, a carrier ring, a radial flange supported by the socket, said flange serving to hold the carrier ring rotatably in assembly with the socket and the handle, the periphery of said ring being sunk between said flange and the handle for preventing rotation of said ring relative to the handle except by the insertion of a tool, at least one pair of axial holes in said ring, retaining means constituted by a U-shaped spring, and a pair of perpendicular projections from the base of said spring spaced to enter said pair of holes and thereby to anchor said spring to the carrier ring with its limbs disposed to pass one through each of said apertured sides into engagement with each of said recesses under a partial relative turning of the handle and the carrier member and to move out of engagement with said recesses and ride on said socket under another partial relative turning of the handle and the carrier member.

18. A door handle assembly comprising, in combination, a spindle, at least one pair of grooves in opposite sides of the spindle, a socket turnable with the spindle and having an opposed pair of apertured sides, a handle turnable with the socket, a carrier member turnable on the socket relative to the handle, said carrier member being sunk within the confines of the handle for preventing rotation thereof relative to the handle except by the insertion of a tool, retaining means constituted by a U-shaped spring, and mutually co-operating recesses and projections on said carrier member and said spring serving to anchor said spring by its base to the carrier member with its limbs disposed to pass one through each of said apertured sides into engagement with each of said grooves under a partial relative turning of the handle and the carrier member and to move out of engagement with said grooves and ride on said socket under another partial relative turning of the handle and the carrier member.

19. A door handle assembly comprising, in combination, a spindle, at least one pair of grooves in opposite sides of the spindle, a socket turnable with the spindle and having an opposed pair of apertured sides, a handle turnable with the socket, a carrier member turnable on the socket relative to the handle, said carrier member being exposed to enable said turns thereof relative to the handle by the fingers.

20. A door handle assembly comprising, in combination, a spindle, at least one pair of grooves in opposite sides of the spindle, a socket turnable with the spindle and having an opposed pair of apertured sides, a handle turnable with the socket, a carrier member turnable on the socket relative to the handle, said carrier member being sunk within the confines of the handle for preventing rotation thereof relative to the handle except by the insertion of a tool, retaining means constituted by a U-shaped spring, and mutually co-operating recesses and projections on said carrier member and said spring serving to anchor said spring by its base to the carrier member with its limbs disposed to pass one through each of said apertured sides into engagement with each of said grooves under a partial relative turning of the handle and the carrier member and to move out of engagement with said grooves and ride on said socket under another partial relative turning of the handle and the carrier member.
